DESIGN FOR A JEWELRY DISPLAY BOX OR SIMILAR ARTICLE

John M. Shields, Chicago, Ill., assignor to F. H.
Noble & Co., Chicago, Ill., a corporation of Illinois

Application April 24, 1936, Serial No. 62,291

Term of patent 7 years

To all whom it may concern:

Be it known that I, John M. Shields, a citizen of the United States, residing at Chicago, in the county of Cook, State of Illinois, have invented a new, original, and ornamental Design for a Jewelry Display Box or Similar Article, of which the following is a specification, reference being had to the accompanying drawing, forming a part thereof.

In the drawing Fig. 1 is a front elevation of a jewelry display box or similar article, showing my new design; Fig. 2 is an end view of the same, and Fig. 3 is a perspective view of the same, showing the box lid slightly elevated.

I claim:

The ornamental design for a jewelry display box or similar article, as shown.

JOHN M. SHIELDS.
